(57) **CLAIM**

The ornamental design for a mobile phone holder, as shown.

DESCRIPTION

FIG. 1 is a front perspective view of a mobile phone holder;

FIG. 2 is a front view thereof;

FIG. 3 is a side view thereof;

FIG. 4 is a rear view thereof;

FIG. 5 is an opposite side view thereof;

FIG. 6 is a bottom view thereof; and,

FIG. 7 is a top view thereof.

The broken lines in FIG. 1 depict environmental subject matter only and form no part of the claimed design.
